UNITED STATES PATENT OFFICE.

DARIUS FAY, OF BINGHAMTON, NEW YORK.

DESIGN FOR A DUST-SCRAPER.

SPECIFICATION forming part of Design No. 28,944, dated June 28, 1898.

Application filed March 5, 1898. Serial No. 672,786. Term of patent 7 years.

To all whom it may concern:

Be it known that I, DARIUS FAY, a citizen of the United States, residing at Binghamton, in the county of Broome, in the State of New York, have invented and produced a new and original Design for Dust-Scrapers, of which the following is a specification, reference being had to the accompanying drawings, forming a part thereof.

Figure 1 is a top plan view of the scraper complete. Fig. 2 is a side view thereof, these two views being deemed sufficient to fully illustrate my design.

As shown in the accompanying drawings, the leading feature of my design consists of a dust-scraper, the body of which is semi-elliptical in form when viewed from a vertical point, said scraper-body being contracted as it approaches the bottom, and is also provided with a handle extending rearwardly at an ob-

tuse angle therefrom, and braces connecting the handle with the scraper-body, the whole forming a unitary article of manufacture.

a is the scraper-body, and *b* the handle.

c are braces connecting the sides of the *25* scraper-body to the handle, and *d* is a strap uniting the scraper-body with the base of said handle, the whole thus formed affording a pleasing effect upon the eye.

Having thus described my invention, what *30* I claim, and desire to secure by Letters Patent, is—

The design for a dust-scraper, substantially as herein described and shown.

In witness whereof I have hereunto set my *35* hand this 8th day of February, 1898.

DARIUS FAY.

In presence of—

JAS. H. CARVER,
H. E. DEDRICK.
